UNITED STATES PATENT OFFICE.

JOSEPH C. FIELD, OF ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,325,192.

Specification of Letters Patent. Patented Dec. 16, 1919.

Application filed May 25, 1917. Serial No. 170,862.

To all whom it may concern:

Be it known that I, JOSEPH C. FIELD, a citizen of the United States, residing at Orange, in the county of Essex and State 5 of New Jersey, have invented certain new and useful Improvements in Telephone Systems, of which the following is a full, clear, concise, and exact description.

This invention relates to telephone systems in which telephone lines may be simultaneously employed for a variety of purposes, such as the transmission of both telegraphic and telephonic messages, and for selective signaling.

15 In telephone systems now in use it is the practice to phantom two metallic telephone lines extending between two widely separated points, for the transmission of telephonic messages therebetween, while employing each telephone line or a portion thereof for the transmission of telephonic messages between points intermediate the terminals of the two lines.

It is the object of the present invention to 25 so equip two such lines, each of which may or may not be simplex for the transmission of telephonic messages between terminals, and each of which may be employed for selective signaling and for the transmission of telephonic messages between any two points thereon, that the telephone lines may be phantomed between either terminal and a point intermediate the terminals, and when so phantomed, to be used for the transmission of separate telephonic messages between the intermediate point and both terminals, or between terminals, without interfering with the use of the lines for selective signaling, and local or through telephone 35 and telegraph messages.

This invention will be fully understood from a consideration of the following description taken in connection with the accompanying drawing, showing one embodiment thereof.

In the drawing there is shown a telephone line comprising line wires 5 and 6, which extends between two points a number of miles apart, for example, between Cincinnati and Columbus. Another telephone line, comprising line wires 7 and 8, extends between the same points.

Each telephone line is equipped with selectors 10, 10, which may be of the type disclosed in the Craft *et al* Patent No. 1,140,120,

and which may be selectively operated by impulses of current transmitted over the respective lines from a battery 11, by the intermittent operation of a relay 12, controlled by an impulse transmitting key 13. Each 60 line at the impulse sending end is equipped with retardation coils 14 and 15 and a condenser 16, for the purpose of graduating the current impulses, in order that they will not cause any disagreeable thump in telephonic 65 apparatus which may be connected with the line wires during the transmission of impulses. A telephone set 17 of the usual construction may be located at the sending end of each telephone line and at each station at 70 which a selector 10 is located.

For the purpose of the transmission of telegraphic messages over each telephone line between terminal stations, each line may be simplex by means of retardation 75 coils 20, one located at each end, each coil being connected between the telephone line and a relay 21 controlled by a telegraph key 22 and controlling a telegraph sounder (not shown). Each retardation coil 20 is non- 80 inductive to currents of telephonic frequency traversing the line wires 5 and 6 or 7 and 8 in parallel, but inductive to such currents traversing the line wires in series. Each winding of the retardation coils 20 is 85 connected with the proper line wire through a condenser 23 and a non-inductive resistance 24. The condenser 23 provides a low impedance path for telephonic currents, and the resistance coil 24, while permitting the 90 passage of direct current, is of sufficient resistance to prevent the undue shunting of the selectors 10. A condenser 25 connected in parallel with each relay 21 and telegraph key 22, furnishes a discharge path by means 95 of which the telegraph impulses are graduated to prevent interference with telephonic apparatus which may be connected with the line wires.

The apparatus hereinbefore described is 100 that commonly employed in systems in which a telephone line is used for the purpose of selective signaling, and the transmission of telephonic and telegraphic messages. The apparatus shown to the left of 105 the dotted line 1—1 is located at one terminal station, while that shown to the right of the dotted line 4—4 is located at the other terminal station. The apparatus shown between the dotted lines 2—2 and 3—3 is 110

located at an intermediate station, for convenience, designated as Xenia.

In order that the sections of the two lines between Cincinnati and Xenia may be employed 5 as a phantom circuit for the transmission of telephonic messages and that the sections of the lines between Columbus and Xenia may also be employed as another phantom circuit for the transmission of telephonic messages, the apparatus, about to be described for isolating the sections to high frequency phantom currents, such as telephonic currents, is provided.

In phantoming the telephone lines, retardation coils 30 non-inductive to currents of telephonic frequency traversing the line wires 5 and 6 or 7 and 8, in parallel but inductive to such currents traversing the line wires in series, have two windings connected 15 with the line wires through condensers 31, 31 which prevent the flow of direct current. Conductors 32 and 37, respectively, connect the windings of the retardation coils 30 and 20 with terminals of jacks 34, each adapted 25 to be engaged by a plug 35 to which is connected a telephone set 36. A condenser 39, in each conductor 37, prevents the passage of direct current. A condenser 33 and a winding of a retardation coil 38 are legged 30 from the conductors 32 and 37 to ground, in accordance with the well-known practice, to prevent the Morse thump from interfering 35 with the phantom telephone circuit. Each winding of each retardation coil 38 is of high impedance to currents of telephonic frequency to prevent the shunting thereof away from the telephone sets 36.

A winding of a retardation coil 40 which is of high impedance to currents of telephonic frequency is in circuit with telegraph relay 21 to prevent the passage of telephonic currents. The windings of the retardation coils 40 are however of low impedance to telegraphic currents.

In order to isolate each telephone line into sections to prevent the passage of phantom currents between sections, retardation coils 41, 41, which are of low impedance to telephonic currents traversing the line wires of 50 each telephone line in series, and to telegraphic currents traversing the line wires in parallel, but of high impedance to phantom telephonic or high frequency currents traversing the line wires in parallel, are included 55 in series with the line wires. In order to prevent such high-frequency currents as may filter through one retardation coil 41 from passing on to the other section, a retardation coil 42 of low impedance to high-frequency currents is connected in bridge of 60 each telephone line between the retardation coils 41, 41, and the middle points of the windings of these coils 42, 42, are connected together by a grounded conductor 43 which 65 serves to practically short-circuit the two

telephone lines to high frequency phantom currents and to balance the lines. Each retardation coil 42 is of high impedance to telephonic currents traversing the line wires of each telephone line in series. The condensers 44, 44 prevent the passage of telegraphic currents.

From this description it will be seen that each telephone line may be employed for the simultaneous transmission of telephone 75 and telegraphic messages, and current impulses for selective signaling while at the same time the two telephone lines may be isolated into sections which are phantom and employed for the transmission of separate 80 telephonic messages between the terminals and the intermediate point at which the lines are divided into sections. It will also be clear from this description that the transmission of these various messages is accomplished without any interference, so that the capacity of existing telephone lines may be increased, thereby avoiding the necessity of building new lines to care for increase in business. Should it be desired at any time 90 to employ the lines for the transmission of telephonic messages between terminal stations over a phantom circuit, this may be accomplished by connecting the two jacks 34, 34 at the intermediate station together by 95 means of a looping cord (not shown). In the same way, either terminal station could be connected with a station on another telephone line which terminates at the intermediate point.

What is claimed is:

1. A telephone system comprising two telephone stations, a pair of conductively continuous line wires joining the stations, and means intermediate the stations for electrically dividing the line wires into sections with respect to high-frequency currents traversing the line wires in parallel, the means electrically separating adjacent sections comprising two retardation coils of high impedance to such currents traversing the line wires in parallel connected in series therewith and a retardation coil of low impedance to such currents connected in bridge of the line wires between the first mentioned coils.

2. A telephone system comprising two stations, two telephone lines joining the stations, each comprising two conductively continuous line wires, signaling and telephonic apparatus in bridge of the line wires of each telephone line responsive to currents traversing the line wires in series, apparatus for phantoming the two telephone lines, telephonic apparatus connected in bridge of 125 the phantom circuit, and means intermediate the stations for electrically dividing the line wires into sections with respect to telephonic currents traversing the phantom circuit, the means electrically separating adjacent sec- 130

- tions comprising two retardation coils of high impedance to such currents connected in series with the line wires of each telephone line and a retardation coil of low impedance to such currents connected in bridge of the line wires of each telephone line between the first-mentioned coils.
3. A telephone system comprising two stations, two telephone lines joining the stations each comprising two conductively continuous line wires, telephonic apparatus in circuit with the line wires of each telephone line responsive to currents traversing the line wires in series, apparatus for phantoming the two telephone lines, telephonic apparatus connected in the phantom circuit, and means intermediate the stations for electrically dividing the line wires into sections with respect to telephonic currents traversing the line wires in parallel, means electrically separating adjacent sections comprising a retardation coil of low impedance to such currents connected in bridge of the line wires of each telephone line and a conductor joining the middle points of the impedance coils.
4. A telephone system comprising two stations, two telephone lines joining the stations each comprising two conductively continuous line wires, telephonic apparatus in circuit with the line wires of each telephone line responsive to currents traversing the line wires in series, apparatus for phantoming the two telephone lines, telephonic apparatus connected in the phantom circuit, and means intermediate the stations for electrically dividing the line wires into sections with respect to telephonic currents traversing the line wires in parallel, the means electrically separating adjacent sections comprising two retardation coils of high impedance to such currents connected in series with the line wires of each telephone line, a retardation coil of low impedance to such currents connected in bridge of the line wires of each telephone line between the first-mentioned coils, and a grounded conductor joining the middle points of the coils of low impedance.

In witness whereof I hereunto subscribe my name this 23rd day of May, A. D. 1917. 50

JOSEPH C. FIELD.
